Primary Examiner — Cynthia Ramirez*Assistant Examiner* — Gino Colan(74) *Attorney, Agent, or Firm* — Cynthia R. Miller(57) **CLAIM**

The ornamental design for a fragrance bottle, as shown and described.

DESCRIPTION

FIG. 1 is a top, front, left side perspective view of our new design for a fragrance bottle;

FIG. 2 is a front elevation view of the fragrance bottle shown in FIG. 1;

FIG. 3 is a rear elevation view of the fragrance bottle shown in FIG. 1;

FIG. 4 is a side elevation view of the fragrance bottle shown in FIG. 1, the other side being identical thereto;

FIG. 5 is a top plan view of the fragrance bottle shown in FIG. 1;

FIG. 6 is a bottom plan view of the fragrance bottle shown in FIG. 1; and,

FIG. 7 is a bottom, front, right side perspective view, showing the fragrance bottle of FIG. 1 in the inverted “in-use” position. The broken lines showing an ovoid-shaped aperture and spray nozzle illustrate environmental structure that forms no part of the claimed design.
